UNITED STATES PATENT OFFICE.

MARTIN BOSNJAK, OF CLEVELAND, OHIO.

DESIGN FOR A WINDOW SHADE AND POLE BRACKET.

52,265.

Specification for Design.

Patented Aug. 20, 1918.

Application filed March 20, 1918. Serial No. 223,669. Term of patent 7 years.

To all whom it may concern:

Be it known that I, MARTIN BOSNJAK, a subject of the King of Hungary, residing at Cleveland, in the county of Cuyahoga and State of Ohio, have invented a new, original, and ornamental Design for Window Shade and Pole Brackets, of which the following is a specification, reference being had to the accompanying drawing, forming part thereof.

Figure 1 is a front perspective view of the window shade and pole bracket.

Fig. 2 is a rear perspective view thereof, and

Fig. 3 is an end elevation of the same.

I claim:—

The ornamental design for a window shade and pole bracket, as shown.

MARTIN BOSNJAK.
